UNITED STATES PATENT OFFICE.

LUDVIG J. W. BIRN, OF CHICAGO, ILLINOIS.

COAL-OIL-GAS BURNER.

SPECIFICATION forming part of Letters Patent No. 416,986, dated December 10, 1889.

Application filed October 22, 1888. Serial No. 283,856. (No model.)

To all whom it may concern:

Be it known that I, LUDVIG J. W. BIRN, of Chicago, in the State of Illinois, have invented certain new and useful Improvements in Coal-Oil-Gas Burners, of which the following is a specification.

My invention relates to that class of oil-burners designed to be placed in the fire-box of an ordinary heating or cooking stove for burning therein oil or gas generated therefrom to heat the stove instead of ordinary fuel; and the object of my improvements is to furnish a burner which will first convert the oil into gas and then burn the same without danger of explosion or waste of oil. I have attained this object in the burner constructed as illustrated in the accompanying drawings, in which—

Figure 1 is a vertical central section of such burner on the line 1 1 of Fig. 3. Fig. 2 is a central vertical section on line 2 2 of Fig. 3. Fig. 3 is a horizontal section through the gas generator or retort on the line at which the cover is attached, and shows an interior plan view of such generator. Fig. 4 is a horizontal section on line 4 4 of Fig. 1, showing a plan of the burner and gas-chamber. Fig. 5 is a central vertical section showing a modification. Fig. 6 is a horizontal section on line 6 6 of Fig. 5. Fig. 7 is a side elevation showing an oil-reservoir connected with the burner as applied in a stove, the latter being shown in a view representing a vertical section through the fire-box.

In the drawings, A designates the gas-generator, which consists of a metal shell made in halves, which are adapted to be connected by bolts or otherwise at a, so as to form a gas-tight chamber within. The lower half of said shell is provided with an interior cup a', which is secured at its bottom to said shell, and extends up nearly to the interior of the shell at the top, forming a chamber a'' outside of said cup and within the shell, which chamber communicates with the interior of the cup through the space between the upper edge of the cup and the interior of the shell at the top. An oil-pipe a³ is extended up through the center of the apparatus and communicates through two large branches a⁴ with said chamber a'' through the open end of said branches at a⁵.

B designates the gas-burner, and C a gas-reservoir. Said reservoir is connected with the gas-generator below the cup a', and has the gas-burners placed around on the outside of it, so that the flame will strike the bottom of said generator. In the connection between the gas-reservoir and said generator there are perforations or openings b b, which form passages from the cup a' to said gas-reservoir, and through the walls of said reservoir and the gas-burner B are perforations through which pipes b' pass for allowing the gas to pass out from said reservoir into said burners. Said burners are open at the bottom, as shown at b², Fig. 1, to allow the air to pass up through them.

The gas reservoir and burners are connected at the bottom with a flange or cup B², adapted to hold a small quantity of oil.

In the modification one enlarged gas-burner B' is placed in the center, with the gas-reservoir C surrounding it, and having the pipes b' projected inward toward the center of such burner. There is a shut-off in the oil-pipe a³ outside of the stove, as shown at d, Fig. 7, whereby the flow of oil is regulated or shut off to put the fire out. The oil may be forced in by gravity when the supply-reservoir D' is elevated above the fire-box of the stove, or by means of air-pressure within the supply-reservoir if it is located on a level with or below the fire-box. Gas is generated from the oil in the enlarged branches a⁴ of the gas-pipe a³, and in the chamber a'' when heated, and passes over into the cup a', and thence down through the pipes b to the gas-reservoir C, said cup serving to retard the flow of oil into said reservoir before being converted into gas or vapor.

The operation is as follows: A little oil is poured in the cup B² and ignited. This heats the bottom of the generator. The shut-off is then opened, so as to allow a little oil to pass in through pipe a³, and when sufficiently heated the oil may be turned on to give the full heating capacity. The gas will be ignited from the flame in the cup B² and continue burning, and keep up the supply after the oil is exhausted from said cup as long as the oil-supply from pipe a³ continues.

What I claim is—

1. In a coal-oil-gas burner, the combination,

with the supply-pipe a^3 , of the oil-reservoir a^4 and chamber $a^2 a'$, placed above said oil-reservoir, the pipes b , and gas-chamber C, said pipes connecting chamber a' with said gas-chamber, and the gas-burners placed beneath said oil-reservoir and having pipes connecting them with the gas-chamber, substantially as shown and described.

- 5 2. In a coal-oil-gas burner, the combination,
10 with the gas-generator A, having two chambers a' and a^2 and an oil-reservoir a^4 , of a gas-

reservoir C, placed below said generator and connected by pipes b with said chamber a' , one or more burners placed under said oil-reservoir and connected by pipes with said gas-reservoir, and an oil-supply pipe connecting said oil-reservoir a^4 with a supply-reservoir, as D', substantially as specified.

15 L. J. W. BIRN.
